UNITED STATES PATENT OFFICE.

JACOB DINER, OF NEW YORK, N. Y., ASSIGNOR TO MANILA STERILIZING CORPORATION, OF MANILA, PHILIPPINE ISLANDS, A CORPORATION OF THE PHILIPPINE ISLANDS.

STERILIZING PROCESS.

1,397,504.

Specification of Letters Patent.

Patented Nov. 22, 1921.

Application filed October 2, 1920. Serial No. 414,258.

To all whom it may concern:

Be it known that I, JACOB DINER, citizen of the United States, and resident of New York, in the county of New York and State 5 of New York, have invented certain new and useful Improvements in Sterilizing Processes, of which the following is a specification.

This invention relates to a process of 10 sterilizing vegetable products by the application of indirect heat, and one object is to provide such a means of sterilization which may be applied to goods manufactured from the vegetable products and while same are 15 in the sealed containers in which the goods are shipped.

A further object is to provide a process 20 which, in its application, will effectively sterilize the packaged products or the goods manufactured therefrom without destroying or impairing, in any degree, the structure or quality of the article itself or damaging the container or package holding same.

An additional object is to provide a process 25 of the character described and for the purpose set forth, which will be expeditious in its application and economical in its cost of operation.

How these objects are attained will be set 30 forth in the following description taken in conjunction with the accompanying drawing, in which;

Figure 1, is a longitudinal section of an 35 apparatus employed in the application of the process, and

Fig. 2, is a transverse section of same, taken along the line 2—2, and looking in the direction indicated.

Referring in detail to the apparatus employed in the process, 10 designates a heating or sterilizing compartment, preferably circular in cross-section and formed with an outer jacket 11, and provided with a closing member 12, which is so constructed and arranged, that when in closed position, it will hermetically seal the compartment. The outer wall may be covered with any suitable heat resisting material 13, preferably asbestos composition.

50 The jacket 11, is provided with a conducting pipe 14, by means of which, steam or other expansible heating fluid is allowed to enter the jacket and an outlet or return conductor 15, may be provided to permit the 55 circulation of the expansible heating fluid

between the sterilizing apparatus and the source of fluid supply. Suitable thermometers, pressure gages, pet cocks and a blow-off valve are provided and arranged to communicate with the jacket and the sterilizing 60 compartment. A portable cage, basket or conveyance 16, may be provided to carry the products to be sterilized, and a pan or trough 17, may also be arranged at the bottom of the compartment for the purpose 65 hereinafter set forth.

In the application of this invention, the apparatus is employed as follows;

The packaged tobacco products to be sterilized are placed within the compartment 70 10, preferably held within any suitable conveyance, as 16, and steam or other expansible fluid is conducted from a generator through the pipe 14, to the jacket 11. The pressure of the fluid may be fixed before it enters the 75 jacket or it may be regulated within the jacket by means of proper valves, operated by hand or under automatic control.

The entrance of the expansible fluid into the jacket will raise the temperature in the 80 compartment and the increase in temperature will be limited by the pressure of the fluid in the jacket. The maximum degree of heat desired within the compartment may be fixed by the pressure of the expansible fluid 85 in the manner above described. The degree of heat maintained within the compartment is dependent upon the product contained therein.

The products are thus subjected to this 90 indirect heating process until the sterilization has been completed. The compartment is then gradually cooled and the products withdrawn.

Any chemical, suitable for the purpose, 95 but preferably tri-chloramin, may be employed as a stimulating element to the sterilization process, by placing the same in the trough or pan 17. The fumes of the chemical, during the heating process, saturate the 100 air within the compartment and thereby enhance the operation.

Various modifications to the process herein described may be embodied without departing from the spirit of the invention and 105 it is therefore not intended that this application be limited to the particular form described.

What is claimed:—

1. The herein described process of steriliz- 110

ing packaged tobacco products, consisting in subjecting the packed tobacco products to a dry heating action, within a hermetically sealed compartment and eliminating therefrom all moisture and moisture producing elements.

2. The herein described process of sterilizing packaged tobacco products, consisting in subjecting the said products to dry fumes 10 of a dry sterilizing chemical contained within a hermetically sealed compartment.

3. The herein described process of sterilizing tobacco products contained in packages,

consisting in subjecting the packages, while in a hermetically sealed compartment, to 15 the action of heat and the fumes from a heated chemical.

4. The herein described process of sterilizing manufactured and packaged tobacco products, consisting in subjecting the said 20 products to the action of dry heated fumes within a sealed compartment.

Signed at New York, in the county of New York and State of New York, this 23rd day of September, A. D. 1920.

JACOB DINER.
